UNITED STATES PATENT OFFICE.

ERNEST WILDHABER, OF ROCHESTER, NEW YORK, ASSIGNOR TO GLEASON WORKS, OF ROCHESTER, NEW YORK, A CORPORATION OF NEW YORK.

METHOD OF PRODUCING CURVED TOOTH GEARING.

Application filed November 8, 1924. Serial No. 748,572.

This invention relates to gearing and more particularly, to the variety having longitudinally curved teeth, one object of the invention being to provide a new and efficient system 5 of gearing of this character together with an improved method for producing the same of a more simple and rapid character than heretofore employed, as well as new and improved tool means for carrying out the novel 10 method.

Another object is the provision of a system of curved tooth gearing produced by a meshing action between cutter and blank based upon the theory of meshing of hyperboloid 15 gears.

Another object is to provide a more simple and expeditious method for producing curved tooth tapered gears. More specifically, it is a purpose of the invention to provide an ad- 20 vantageous method for producing such gears in which one of a mating pair is cut by a continuous indexing rotation of tool and blank combined with a simple relative feeding movement therebetween without the usual 25 generating roll, with the resultant advantages of increased simplicity and speed of production.

Another object is to provide a method of 30 producing tapered gears comprising the use of the advantageous principle of simultaneous rotation of tool and blank in continuous cutting and indexing relation, in combination with the use of a gear so cut as the basis of the system of gearing of which it forms a 35 part.

A further object is to provide practical and economical tool means for carrying out the above method and specifically a hobbing cutter of a form adapted to be easily manufac- 40 tured and maintained in condition in use. To these and other ends the invention resides in certain improvements and combinations of parts, all as will be hereinafter more fully described, the novel features being pointed 45 out in the claims at the end of the specification.

In the drawings:

Figure 12 is a side view of the same with the cutting blades in section to further illustrate their character and arrangement; 75

Figure 13 is a diagrammatic view illustrative of certain structural details of the hob;

Figure 14 is an elevation of a curved tooth 80 beveled gear produced in accordance with and embodying the present invention, and showing schematically a hobbing cutter arranged in cutting contact therewith;

Figure 15 is a sectional plan view of the 85 gear on the line 15^a—15^b in Figure 14, and

Figure 16 is a sectional plan view of a portion of the gear on the line 16^a—16^b in Figure 14.

Similar reference numerals throughout the 90 several views indicate the same parts.

The present invention is a result of efforts to simplify and expedite and cheapen the commercial production of efficient curved tooth gears, and of an analysis to that end of the theory of action of hyperboloid gearing. The latter involves the meshing of a pair of gears with the axis of one offset from that of the other, and the present method involves the cutting of curved tooth bevel gears by an analogous arrangement in which the axis of the tool is offset from that of the gear blank.

While the invention may be carried out by the use of various tool means, it has been discovered that one advantageous embodiment comprises the use of a tapered hob and that such a hob can be made to mesh along a straight line with a gear of suitable construction which forms the basis of the system of gearing produced and can be cut and finished by the hob in complete form without resort to the usual generating roll. The present embodiment of the invention in conjunction with the use of such a hob is illustrated diagrammatically in Figures 1 to 6 and will first be described in a more general way, followed by a particular description of the principles involved as well as of the hobbing cutter and the gears produced thereby in accordance with the method.

Figure 1 shows in plan view a tapered hob 20 arranged in cutting contact with a bevel gear blank 21, with the axis 22 of the hob offset from the axis 23 of the gear, as more particularly described hereafter. The hob and blank are rotated about their respective axes in timed, intermeshing relation to effect a continuous cutting and indexing action between the teeth of the hob and those to be cut in the blank, and a relative feeding movement is simultaneously produced between the hob and blank parallel with the axis 23 of the latter to obtain the desired tooth height, so that in effect, the hob is sunk into the blank to the full depth of the teeth being cut. It is to be noted that the manipulation of the hob and blank comprises exclusively the cutting and indexing rotation and the simple feeding movement described which may be rapidly accomplished without the necessity of resort to the time consuming relative rolling movement between the parts commonly required to generate the tooth profiles. The hob is formed by longitudinally gashing and relieving a tapered worm to produce cutting portions of rack section and constant pitch in a plane offset from the axis of the hob, as more fully described hereafter. The gear produced is a curved tooth bevel gear of rack section and uniform pitch along a straight line in a plane offset from its axis and inclined with respect to the projection of its axis in said plane, as more fully appears hereinafter.

It has also been found that another hob can be made to mesh with hob 20 in the same way that the latter meshes with the basic gear 21. That is to say, a second or counter hob 24, Figures 3 and 4, can be made to mesh internally with and sweep out the teeth of the basic gear 21 so as to represent the latter when swung about its axis 23. A counter hob of this nature may therefore be employed, Figures 5 and 6, to cut a gear or pinion capable of meshing correctly with the basic gear 21. In cutting the mating gear

25 the counter hob and blank are rotated about their respective axes 26 and 27 to produce a continuous intermeshing indexing of the hob and blank teeth while a relative generating roll is produced between the hob and blank about the axis 23 of the imaginary gear 21 upon which the mating gear 25 may be assumed to roll. The angle between the axis 27 of the mating gear and axis 23 is a right angle, as shown in Figure 6, and the generating roll about axis 23 is added to or subtracted from the indexing rotation of the hob or blank 25 rolled about this axis. It will thus be seen that the gear 21, which serves as the basis of the system is cut in a simple and rapid manner by merely sinking the hob into it without the generating roll, while the mating gear or pinion 25 is cut with a similar hob in a rapid and practical manner, involving a relative generating roll of which the mating gear is the basis.

The principles involved in the above described method of producing the gearing are best explained by a consideration of the theory of meshing of hyperboloid gears which latter may be described generally as gears having tapered body portions rotating on non-intersection axes. Such gears approach the nature of beveled gears where the distance between the axes of the mating pair is comparatively small and they approach the form of worm gears as such distance becomes large. Thus in Figures 7 and 8, 28 and 29 represent a pair of such gears in intermeshing relation. Gear 28 rotates upon an axis A while gear 29 rotates on an axis A_o, which axes are parallel to the plane of the paper in Figure 7, but are offset from one another at a distance E as shown in Figure 8. Let N represent the number of teeth in gear 28 and N_o the number of teeth in gear 29, so that the tooth ratio is N/N_o. The tooth shapes and characteristics of mesh depend solely upon the above ratio, but for convenience in the following explanation, a velocity analysis will also be made.

If a point P, Figures 7 and 8, be assumed to travel in space along any assumed line, it will trace a relative path with respect to gear 28 and another relative path with respect to gear 29, which paths join at P. Such a point P can be a point of mesh between the two gears when the tangents to the two relative paths coincide, that is when these paths have a common tangent at P, the tooth inclination being assumed at will. The relative sliding velocity is in the direction of the common tangent. The direction of a tangent to the relative path is identical with the direction of the relative velocity and the existence of a common tangent at P therefore indicates relative velocities having the same direction.

Let it be further assumed that the absolute path of point P is in a plane parallel to the

axes A and A_o and that convenient symbols be employed as follows:

W=absolute velocity of P in a plane parallel to axes A and A_o.

α, α_o =angles between the direction of W and the axes A and A_o, respectively.

V_s=relative velocity component of P with respect to gear 28 in the direction of W.

V_n=relative velocity component of P with respect to gear 28 perpendicular to W in a plane parallel to axes A and A_o.

V_z=relative velocity component of P with respect to gear 28 in the direction Z, or perpendicular to a plane parallel to axes A, A_o.

V_{so}, V_{no}, V_{zo}=corresponding components of relative velocity of P with respect to gear 29.

Ω, Ω_o =angular velocities of gears 28 and 29, respectively.

Z, Z_o=constant vertical distances of plane of travel of P from axes A and A_o, respectively.

d, d_o=distances of P from axes A and A_o respectively in horizontal projection, Figure 7.

Then, with the indicated directions of revolution, the following values of component velocities obtain for the axes A and A_o:

For A:-

$$V_s = W - Z \Omega \sin \alpha$$

$$V_n = +Z \Omega \cos \alpha$$

$$V_z = -d \Omega$$

For A_o:-

$$V_{so} = W - Z_o \Omega_o \sin \alpha_o$$

$$V_{no} = -Z_o \Omega_o \cos \alpha_o$$

$$V_{zo} = d_o \Omega_o$$

Taking up first the condition represented by the equation

$$\frac{V_{no}}{V_{zo}} = \frac{V_n}{V_s}$$

the above values may be substituted therein to give after reduction, the following equation:-

$$\frac{d_o}{d} = \frac{Z_o \cos \alpha_o}{Z \cos \alpha}$$

The last equation is a constant, " α_o " and "a" being assumed constant. For other points in the same plane, as P', Figures 7 and 8, the ratio $\frac{d_o}{d}$ is always the same, hence all such points lie in a straight line G passing

through the point O, and only points lying in such straight lines are capable of producing relative paths with a common tangent. Hence line G is the line of action and the two pitch hyperboloids contact with one another along the straight line of action G and the threads or teeth of corresponding gears can mesh along this line. The location of the line can be found by letting "S" represent the distance of point P from O, so that

$$\frac{d_o}{d} = \frac{S \sin \alpha_o}{S \sin \alpha} = \frac{Z_o \cos \alpha_o}{Z \cos \alpha}, \text{ whence } \frac{\tan \alpha}{\tan \alpha_o} = \frac{Z}{Z_o}$$

Line G is the generatrix of the pitch surfaces of the gears, which are hyperboloids since the line is offset from the axis of each.

Taking up the second condition represented by the equation

$$\frac{V_{so}}{V_{zo}} = \frac{V_s}{V_z} \quad 80$$

and the relations

$$\frac{W}{\Omega_o} = \frac{LN_o}{2\pi}, \text{ and } \frac{W}{\Omega} = \frac{LN}{2\pi} \quad 85$$

where L=lead per tooth and N_o, N=the number of teeth, by substituting the above values and reducing expressions for the values of Z_o and Z can be readily obtained as follows:-

$$Z_o = \frac{\tan \alpha_o}{\tan \alpha + \tan \alpha_o} \times \frac{L}{2\pi} \left(\frac{N_o}{\sin \alpha_o} + \frac{N}{\sin \alpha} \right) \quad 90$$

$$Z = \frac{\tan \alpha}{\tan \alpha + \tan \alpha_o} \times \frac{L}{2\pi} \left(\frac{N_o}{\sin \alpha_o} + \frac{N}{\sin \alpha} \right) \quad 95$$

By adding these equations the following expression is obtained for the center distance E=(Z+Z_o), Figure 8:-

$$\frac{L}{2\pi} \left[\frac{N_o}{\sin \alpha_o} + \frac{N}{\sin \alpha} \right] \quad 100$$

It is to be noted that all of the other factors of the above equation being constants, the lead L also is constant, and the gears will have a constant pitch along line G.

Gear 29 can also be considered as a hob. This hob will therefore have a constant pitch along line G and is preferably of rack section along the latter, and will therefore produce a gear whose teeth are of constant pitch and rack section along the line of action. It can mesh in the same way with different gears 28 so long as their angles "a" and tooth numbers N fulfill the equation given above for Z_o. The number N can be expressed as a function of "a" as follows:-

$$N = \left[\tan \alpha \left(\frac{2\pi Z_o}{L} \times \frac{1}{\tan \alpha_o} \right) + \frac{2\pi Z_o}{L} - \frac{N_o}{\sin \alpha_o} \right] \sin \alpha \quad 110$$

Hobs are commonly single threaded, that is, single threaded or as a hob and will for convenience be referred to in this aspect as the

counter hob as shown at 28'; Fig. 9. Hob and counter hob may mesh with one another along the same line G. Along this line the counter hob will therefore have the same pitch and rack section as the gear 28 itself and it is therefore capable of representing the gear, in cutting a mating gear, when given suitable generating or feeding motion about the axis of said gear. The counter hob must 10 of course fulfill the above equation for N. It is therefore possible to hob a gear, preferably the larger gear of a pair without additional generating roll and to cut the mating gear with the counter hob with a relative 15 generating movement about the apex of the blank as if the blank were rolling on its mating gear, as described above in connection with Figures 1 to 6 inclusive.

As already stated, the rotation of the line 20 of action G about the axis of the gear generates a hyperboloidal surface. This is shown at 30, Fig. 10, in connection with a hob 31 embodying the invention, and at 32, Fig. 15, in connection with a gear 33 produced thereby. 25 The angle "a" and the offset Z are so chosen that the said hyperboloidal surface approximates either the pitch cone of the gear or the conical surfaces which lies midway between the root and face cones of the gear. The profile 32 of such hyperboloidal surface is shown in dotted line as tangent to the profile 34, Fig. 15, of the latter of such conical surfaces.

The tapers of hob and counter hob can be made alike when the hob is given characteristics corresponding to the above equation for the value of Z_0 which reduces, N_0 being equal

40 to unity, to the form $\sin a_0 = \frac{L}{2\pi Z_0}$. In this case the formula for N given above reduces to

$$N = \frac{\cos a_0 \times \sin^2 a}{\sin^2 a_0 \times \cos a}$$

In practice the hob and counter hob are 45 preferably alike in construction and in fact one and the same hob is employed as both hob and counter hob. This hob will cut the gear without generating roll and the mating pinion with a generating roll corresponding to the mesh between the gear and pinion, or, in 50 other words, as if the pinion were rolling on the gear in accordance with the principles already described in connection with Figs. 5 and 6, where however the relative roll between hob 24 and pinion 25 is in the equivalent 55 form of actual rolling of the hob.

The construction of the hob is shown in 60 Figures 10 to 13 inclusive as having generally the form of a tapered worm gashed longitudinally or fluted as at 35 and relieved as shown to produce cutting blades 36 of rack section and constant pitch in a plane 13^a—13^a, Fig. 11, offset from the axis A₀ of the hob a distance Z_0 as heretofore described. The cutting faces 37 of the teeth are preferably 65 though not necessarily located in said plane.

The hob meshes along this offset straight line of action and is preferably provided with rake or hook flutes, that is, with non-radial flutes 35, as shown in Figure 11, which contain the line of action and are parallel to the 70 hob axis. The relieving tool 38 is led at uniform lead along the line of action and is preferably positioned above center corresponding to the desired offset of the hob. With the use of such rake flutes, improved cutting qualities 75 are combined in this type of tapered hob with mathematical correctness. Figure 13 shows diagrammatically one of the straight flutes having cutting portions of uniform pitch or lead and preferably rack section. The hob 80 can cut gears of various tooth numbers N and taper angles "a" bearing the relations expressed in the simplified equation for N already given. The taper angle "a" (not the cone angle) may be accurately determined by 85 solving for "a" in the last equation for N above. The angle "a" is required for hob settings. In cutting the gear the hob distance is $Z + Z_0$ which can be obtained from the above equations. The inclination of the hob axis 90 is $a_0 - (90^\circ - a)$. In cutting the pinion, the hob distance is $Z - Z_0$ and the inclination of the hob axis is $a_0 + (90^\circ - a)$. A hob can cut practically all gears corresponding to pinions 95 of a given tooth number irrespective of their cone angles and a wide range of gears can therefore be cut with comparatively few hobs.

The gear produced by the above method and hob means is illustrated in Figures 14, 15 and 16 which show the line of action G in a 100 plane offset from the axis of the gear and inclined with respect to the projection of said axis in said plane. The teeth are of rack section and uniform pitch in such line and it follows from the method described that the 105 teeth of the gear are of substantially straight profile and noncircular lengthwise curvature and therefore of constantly changing radius. A section through the gear in a plane passing through a plurality of its teeth, as shown for 110 example in Fig. 16, is of the same general form as a corresponding section through the hob employed to produce it. When the same hob is used for cutting gear and pinion as is preferable, the data of the gear fulfill the 115 following equation

$$Z = \frac{L}{2\pi \sin a} \times N$$

which may be readily derived from the above 120 equations. It follows also that the gear is adapted to mesh selectively with either a spiral bevel pinion or a taper worm, corresponding to the hob. The simple feeding movement without generating roll by which 125 the gear is cut as described above and the arrangement of the hob during such cutting, in contact with the whole tooth surface, makes it practical to employ a high rate of feed which is preferably reduced as the teeth near 130

completion for the purpose of completing the work with the desired finish. The described method is not only capable of being carried out by application to known forms of gear cutting machines and by simple and practical hobbing tools, but also affords rapid production with a substantial decrease in cost and furthermore produces an efficient system of gearing applicable to a wide variety of uses.

I claim as my invention:

1. The method of cutting a gear blank consisting in employing a cutter having a uniform pitch along a line in a plane offset from its axis and inclined to the projection of its axis in said plane, and in rotating said cutter in engagement with the blank.

2. The method of cutting a gear blank consisting in employing a cutter having a uniform pitch along a line in a plane offset from its axis and inclined to the projection of its axis in said plane, in rotating said cutter in engagement with the blank, and in simultaneously effecting a relative feeding movement therebetween to obtain the desired height of tooth.

3. The method of cutting a gear blank consisting in employing a hob having a uniform pitch along a line in a plane offset from its axis and inclined to the projection of its axis in said plane, and in rotating said hob and blank in continuous cutting engagement with each other.

4. The method of cutting a gear blank consisting in employing a hob having a uniform pitch along a line in a plane offset from its axis and inclined to the projection of its axis in said plane, in rotating said hob and blank in continuous cutting engagement with each other, and in simultaneously effecting a relative feeding movement therebetween to obtain the desired tooth height.

5. The method of cutting a gear blank consisting in employing a hob having a uniform pitch along a line in a plane offset from its axis and inclined to the projection of its axis in said plane, in rotating said hob and blank in continuous cutting engagement with each other, and in simultaneously effecting a relative feeding movement therebetween to obtain the desired tooth height while maintaining a fixed angular relation between the hob and blank axes so that in finish cutting position the hob sweeps the entire width of the tooth surface.

6. The method of cutting a gear which comprises rotating a taper hob of constant pitch in a plane offset from its rotary axis in cutting engagement with a rotating blank.

7. The method of cutting a gear consisting in rotating a taper hob of constant pitch in a sectional plane offset from its rotary axis in cutting engagement with a rotating blank while maintaining a fixed angular relation between the hob and blank axes.

8. The method of cutting a gear consisting in rotating a taper hob of constant pitch in a sectional plane offset from its rotary axis in cutting engagement with a rotating blank and simultaneously effecting a relative feeding movement between the hob and blank to obtain the desired tooth height while maintaining a fixed angular relation between their axes.

9. A method of cutting a pair of gears comprising cutting teeth in one gear with a taper hob by rotating said hob in continuous meshing engagement with a continuously rotating tapered gear blank and cutting the teeth of the other gear with a hob of the same hand as the first hob by rotating said latter hob in continuous engagement with a rotating gear blank while imparting a relative rolling movement between the latter hob and the blank.

10. The method of cutting a tapered gear which consists in rotating a hob in continuous cutting engagement with a rotating blank while imparting an additional relative movement between hob and blank as if said blank were rolling with its mate gear.

11. The method of cutting a pair of gears which comprises cutting one member of the pair by rotating a hob in cutting engagement with a rotating blank and cutting the other member by rotating a hob of the same hand in cutting engagement with a rotating blank while imparting an additional relative movement between tool and blank as of a cone rolling on the first gear.

12. A method of cutting a pair of gears which comprises rotating a taper hob in engagement with a rotating blank and cutting the other gear by a taper hob of the same hand rotated in engagement with a rotating blank while imparting an additional relative movement between the hob and blank as of a gear rolling on the first gear.

13. A method of cutting a pair of gears which comprises cutting one member of the pair by rotating a taper hob in engagement with a rotating blank and cutting the other member of the pair by rotating a taper hob adapted to mesh with the first hob in engagement with a rotating blank while imparting an additional relative movement between said second hob and blank in the manner of a gear rolling on the first gear.

14. The method of cutting a pair of bevel gears which comprises cutting one member of the pair by rotating a hob in continuous engagement with a rotating blank while maintaining the axis of the hob in offset relation to the axis of the blank and cutting the other member by rotating the hob which is adapted to mesh with the complement of the first gear in continuous cutting engagement with a rotating blank while maintaining the axis of the hob in offset relation to the axis of the blank and imparting an addi-

tional relative movement between hob and blank as of a gear rolling on the first gear.

15. The method of cutting a pair of bevel gears which comprises cutting one member 5 of the pair by rotating a taper hob in continuous engagement with a rotating blank while maintaining the axis of the hob in offset relation to the axis of the blank and cutting the other member by rotating a hob of 10 the same hand as the first hob in continuous cutting engagement with a rotating blank while maintaining the axis of the hob in offset relation to the axis of the blank and imparting an additional relative movement between tool and blank as of a gear rolling on 15 the first gear.

16. The method of cutting a beveled gear having a uniform pitch along a straight line in a plane offset from its axis and inclined to 20 the projection of its axis in said plane, which consists in rotating a taper hob in engagement with said blank, said hob having the same uniform pitch along a straight line in a plane offset from its axis and inclined to 25 the projection of its axis in said plane, the offsets Z and Z_0 of the line of constant pitch from the axes of the blank and hob respectively and the inclination angles α and α_0 bearing substantially the following relation 30 to one another,

$$\frac{\tan \alpha}{\tan \alpha_0} = \frac{Z}{Z_0}$$

17. The method of cutting a pair of gears 35 having longitudinally curved teeth comprising cutting one of the pair by rotating a taper hob and a gear blank in continuous intermeshing engagement while imparting a relative feed movement between said hob and blank so that in finish cutting position the hob sweeps out the whole finished tooth surface of the blank, and in cutting the other member of the pair by rotating a taper hob and a gear blank in continuous intermeshing 40 engagement while imparting a relative rolling movement between said hob and blank in the manner of a gear meshing with its mate gear.

18. The method of cutting a pair of gears 50 comprising cutting one member of the pair with a taper hob of constant pitch by rotating said hob in intermeshing engagement with a continuously rotating gear blank while imparting a relative feed movement between said hob and blank so that in finish cutting position the hob sweeps out the whole finished tooth surface of the blank, and in cutting the other member of the pair by rotating a taper hob of constant pitch in intermeshing 55 cutting engagement with a continuously rotating gear blank while imparting a relative rolling movement between said hob and blank in the manner of a gear meshing with its mate gear.

19. The method of cutting a pair of gears

having longitudinally curved teeth comprising cutting one member by rotating a tool, having its cutting portions arranged in a continuous thread, in continuous intermeshing engagement with a rotating gear blank while imparting a relative feed movement between said tool and blank parallel with the blank axis so that the tool in finish cutting position sweeps out the whole finished tooth surface of the blank, and in cutting the other member by rotating a tool of the same structure as the first tool in continuous intermeshing engagement with a rotating gear blank while imparting a relative rolling movement between said tool and blank in the manner of a gear meshing with its mate gear.

20. The method of cutting a gear having longitudinally curved teeth comprising employing a taper hob, of a construction other than that of the gear with which the gear being cut is to mesh, and rotating said hob in intermeshing engagement with a continuously rotating gear blank while imparting a relative feed movement between said hob and blank so that in finish cutting position the hob will sweep out the whole finished tooth surface of the blank.

21. The method of cutting a pair of gears having longitudinally curved teeth comprising cutting one member by rotating a tool, having its cutting portions arranged in a continuous thread, in continuous intermeshing engagement with a rotating gear blank while imparting a relative feed movement between said tool and blank so that in finish cutting position the tool sweeps out the whole finished tooth surface of the blank, and in cutting the other member by rotating a tool, having its cutting portions arranged in a continuous thread, in continuous intermeshing engagement with a rotating gear blank while imparting a relative rolling movement between said last named tool and blank in the manner of a gear meshing with its mate gear.

22. The method of cutting a gear provided with longitudinally curved teeth on its side face which consists in rotating a hob of constant pitch in a plane offset from its axis in continuous cutting and indexing engagement with a gear blank while maintaining the axis of the hob in fixed offset and angular relation to the axis of the blank so that in finish cutting position the hob sweeps out the whole finished tooth surface of the blank.

23. The method of cutting a gear provided with longitudinally curved teeth on its side face which consists in rotating a hob of constant pitch in engagement with a continuously rotating gear blank while imparting a relative rolling motion between the hob and blank in the manner of a gear meshing with its mate gear.

24. The method of cutting a gear provided with longitudinally curved teeth on its side face which consists in rotating a hob of con-

stant pitch in a plane offset from its axis in engagement with a continuously rotating gear blank while imparting a relative rolling motion between the hob and blank in the 5 manner of a gear meshing with its mate gear.

25. The method of cutting a longitudinally curved tooth tapered gear which consists in rotating a taper hob in engagement with a continuously rotating gear blank while imparting 10 a relative rolling motion between the hob and blank in the manner of a gear meshing with its mate gear.

26. The method of cutting a longitudinally curved tooth tapered gear which consists in 15 rotating a taper hob of constant pitch in engagement with a continuously rotating gear blank while imparting a relative rolling motion between the hob and blank in the manner of a gear meshing with its mate gear.

20 27. The method of cutting a longitudinally curved tooth tapered gear which consists in rotating a taper hob of constant pitch in a plane offset from its axis in engagement with a continuously rotating gear blank while 25 imparting a relative rolling motion between the hob and blank in the manner of a gear meshing with its mate gear.

28. The method of cutting a pair of gears which consists in cutting one member of the pair by rotating a hob in engagement with a continuously rotating gear blank while maintaining the angular relation between the hob and blank axes fixed, so that in finish cutting 30 position the hob sweeps out the whole finished tooth surface of the blank, and in cutting the other member of the pair by rotating a hob in engagement with a continuously 35 rotating gear blank while imparting a relative rolling motion between the hob and blank.

29. The method of cutting a pair of gears 40 which consists in cutting one member of the pair by rotating the hob in engagement with a continuously rotating gear blank while maintaining a fixed angular relation between the hob and blank axes, so that in finish cutting 45 position the hob sweeps out the whole finished tooth surface of the blank, and in cutting the other member of the pair by rotating a hob in engagement with a continuously 50 rotating gear blank while imparting a relative rolling motion between the hob and blank as of a gear rolling on the first gear.

ERNEST WILDHABER.
